MOSES L. HAWKS, OF NEW YORK, N. Y.

SHARPENING DEVICE.

1,088,986.

Specification of Letters Patent.

Patented Mar. 3, 1914.

Application filed February 19, 1913. Serial No. 749,405.

To all whom it may concern:

Be it known that I, MOSES L. HAWKS, a citizen of the United States, and a resident of New York city, borough of Manhattan, in the county of New York and State of New York, have invented certain new and useful Improvements in Sharpening Devices, of which the following is a specification.

This invention relates to sharpening devices, more particularly to a combined device for sharpening knives and scissors or any other similar instrument requiring a sharp edge.

The principal object of the present invention is to provide a very simple and efficient sharpener for knives, scissors or other similar instruments adapted to be combined with a hone utilized as a finisher, the sharpening member being adjustable so as to present a new surface whenever the old surface has become worn.

Further objects and advantages will appear from the following detailed description of my invention, and the features of novelty will be particularly pointed out in the appended claims.

Referring now to the accompanying drawings, Figure 1 is a plan view of my improved combined device. Fig. 2 is a longitudinal section taken along the line 2—2 of Fig. 1, looking in the direction of the arrows. Fig. 3 is a transverse sectional view taken along the line 3—3 of Fig. 2, looking in the direction of the arrows. Fig. 4 is a detail view of the sharpening member. Fig. 5 is a detail view of the H-shaped blank from which is formed the channel or holder for the sharpening member. Fig. 6 is a detail view of the channel or holder for the sharpening member shown in its proper form ready for insertion in the handle. Fig. 7 is a fragmental sectional view illustrating a modification of my invention.

Referring to Figs. 1 and 2, the handle 1 has a longitudinal socket at one end thereof adapted to receive the shank of the hone 2. Near the opposite end of the handle 1 is a transverse aperture 3, which is adapted to receive the channel or holder 4, which in turn receives and embraces the sharpening member 5. The latter may conveniently consist of a steel file which may be used for roughing off the edge to be sharpened, this edge being then finished on the hone. The sharpening member may be held in position in the channel or holder 4 by means of a

set screw 6 extending into the outer end of the handle. The set screw may be turned to bear tightly against the side 7 of the holder 4, thus clamping the steel in place. When the exposed portion of the sharpening member becomes worn a new surface may be presented by unclamping the holder and adjusting the sharpening member to a new position. The ends of the sides 7 of the holder 4 are bent at an angle to form guides 8 for the knife, and guides 8^a for the scissor or similar edged instrument to be sharpened. The channel or holder 4 may easily be inserted in the aperture 3 when in the form shown in Fig. 6, the ends 8 only being there shown as inclined. The ends 8^a are bent after they are inserted in the aperture, and thus form positive means for keeping the channel or holder rigidly in position and retain it from displacement. It will be noted that the guides 8 are at a more acute angle than the guides 8^a, as shown clearly in Fig. 2. The former constitute the guides for a knife and the latter are for a scissor or similar edged instrument. Grooves 9, formed about the handle, also serve to guide the instrument to be sharpened and maintain it snugly against the sharpening surface.

It will be seen from Figs. 1 and 3 that the longitudinal socket of the handle 1 is provided with two slits 10, dividing the socket into two portions. When these two portions are pressed together the diameter of the socket is necessarily lessened, so that the shank of the hone 2, when inserted in the socket, may be gripped tightly, if pressure is brought to bear upon the two sections of the socket. This result is effected by the metal collar 11, which is of slightly less diameter than the surface of the part of the handle upon which it is driven. The end of the handle is beveled at 12, and the collar is also beveled to conform therewith, thus securing a greater gripping force upon the hone shank at that point. Encircling the hone between the shoulder thereof and the end of the handle is a shield 12^a having radial arms or projections. These arms effectively protect the hand holding the handle when the knife, scissor, or other similar instrument is being honed. The hone 2 is preferably formed of plastic composition reinforced by a steel core 13 to render it less liable to breakage.

The sharpening operation is accomplished as follows: The handle is gripped with one

hand, while the knife, scissor, or other similar instrument is held with the other and placed with one side flat against the guide 7, the edge of the instrument to be sharpened 5 being in contact with the sharpening surface, as shown by the dotted lines 14 in Fig. 2. By pulling the blade back and forth, first on one side of the sharpening member 5 and then on the other, and pressing the 10 same downward against the sharpening surface, a sharp edge will be obtained. The edge may then be finished off on the hone to make it smooth and keen, a very few strokes being sufficient.

15 In the modification shown in Fig. 7 the set screw 6 operates in a bushing 15 sunk in the outer end of the handle. Otherwise the construction is the same as in the other form illustrated and described above.

20 From the above description it will be readily apparent that I have provided a sharpener which is simple and inexpensive in construction and very efficient in operation. The parts are very easily adjustable, 25 as well as renewable. By securing the holder in the aperture by means of the guides, any outside means for securing the same is dispensed with. The facility with which the sharpening member may be re-

30 leased, moved to a new position presenting a new and unused sharpening surface, and there rigidly clamped by the set screw, enhances the utility of the device. The cost of manufacture is very low, as substantially 35 all of the operations in forming the parts,

and the assembling of same, may be readily accomplished in dies and jigs.

I claim as my invention:

1. In combination with a handle having a transverse aperture adjacent one end, of a 40 channeled holder within the aperture, said holder being provided with angular flaring end portions for retaining the same in position, and a sharpening member adjustably held in said holder, means for clamping the 45 holder against the sharpening member, said flaring end portions serving as guides for the instrument to be sharpened.

2. In combination with a handle having a 50 transverse aperture adjacent one end, of a holder formed of spring sheet metal, said holder having a channeled body portion passing through the aperture, angular flaring end portions formed on the holder adjacent to the mouths of the aperture, a 55 sharpening member adjustably held in said holder, and means for springing the body portion so as to clamp the sharpening member in adjusted position to present a fresh sharpening surface, the flaring end portions 60 serving as guides for the instrument to be sharpened.

Signed at New York city, in the county of New York and State of New York, this 18th day of February, 1913.

MOSES L. HAWKS.
